UNITED STATES PATENT OFFICE.

HENRY G. VOLKMAR, OF NEW YORK, N. Y., ASSIGNOR TO HIMSELF AND JAMES P. PAYNE, OF SAME PLACE.

COUPLING.

SPECIFICATION forming part of Letters Patent No. 674,389, dated May 21, 1901.

Application filed August 9, 1900. Serial No. 26,345. (No model.)

To all whom it may concern:

Be it known that I, HENRY G. VOLKMAR, a citizen of the United States, residing in the city of New York, borough of Manhattan, in 5 the county and State of New York, have invented a certain new and useful Improvement in Couplings, of which the following is a specification.

The invention relates to means for joining 10 metal pipes to earthenware or other fragile receptacles, and is designed more particularly for plumbers' use in joining discharge-pipes to crockery hand-basins.

The invention consists in certain details of 15 construction to be hereinafter described.

The accompanying drawings form a part of this specification and show what I consider the best means of carrying out the invention.

Figure 1 is a vertical section through a 20 hand-basin equipped with my improved coupling, the latter being shown in elevation. The remaining figures are on a larger scale. Fig. 2 is a central vertical section through the coupling alone. Fig. 3 is a transverse section taken on the line 3-3 in Fig. 2, showing the corrugations on the under side of the flange. Fig. 4 is a plan view of a portion of the basin similarly corrugated. Fig. 5 is an elevation of the helical spring.

25 Similar letters of reference indicate the same parts in all the figures.

A is the ordinary slab of a basin, supported on brackets or standards, (not shown,) and B is the basin, joined thereto by any ordinary or 30 approved fastenings. The basin shown is of the type most difficult to connect without breaking, in which the overflow-orifices b lead to a passage B', formed in the material of the basin and communicating with the discharge- 35 passage through the recess B³ between the horizontal partitions B⁴ B⁵, surrounding the discharge-orifice B⁶. The upper face of the partition B⁴ is corrugated radially, as shown at B⁷ in Fig. 4, while the under face of the 40 lower partition B⁵ is plane.

C is a metallic tube having a slightly-tapered seat C' at the upper end adapted to receive the ordinary plug (not shown) and surrounded by an annular flange C², having the 45 radial corrugations C⁸ on its under face to match the corrugations on the basin. Be-

low the plug-seat C' the metal of the tube is cut away on opposite sides, as indicated at C⁴ and C⁵, to provide inlet-orifices for the waste from the overflow, as usual.

55

C³ represents the ordinary cross-bar, serving to arrest solid matter.

The main portion C of the tube is shown as screw-threaded, as usual, but may be smooth throughout the upper portion of its length 60 and have only sufficient threads at the lower end to receive the nut D' of the union D, connecting to the main discharge-pipe (not shown) in any suitable manner.

M is a stiff helical spring inclosing the tube 65 C and exerting its force expansively between the under face of the basin and the nut D'. The spring should have sufficient length to allow considerable shortening by compression before its coils contact with each other, thus 70 allowing the nut to be traversed some distance upon the tube and correspondingly increasing the thrust of the spring, while still maintaining sufficient resiliency to avoid danger of fracturing the basin at the point of contact.

In applying the coupling a soft washer E, 75 of rubber or other suitable material, is laid upon the corrugations of the upper partition B⁴, and the tube C is then passed downward 80 through the washer and discharge-orifice until the flange C² rests upon the washer and is then turned until its corrugations match those in the basin. The washer F, having a soft facing F', of rubber, is next applied from 85 below, encircling the tube C and having its soft face next to the plane under face of the partition B⁵. The spring M is next passed over the end of the tube and the nut D' of the union D is engaged with the threads thereon. Screwing the nut upward compresses the 90 spring M and draws the flange C² into its socket in the basin, forcing the corrugations on each into the soft washer E, and thus making a water-tight joint. The washer F F' is thrust 95 with equal force against the under face of the basin. The nut D' may be screwed home with perfect freedom, the result being a further compression of the spring with a corresponding increase of tension and a tightening of the 100 joint without danger of fracturing the basin.

The spring is preferably formed with the off-

sets M' M², introduced to allow the upper and lower turns to lie in a plane with their respective bearing-surfaces.

I can omit the corrugations on the flange or 5 on the basin, or on both, if preferred, depending on the friction of the washer E to prevent turning, or the washer may be dispensed with and its place taken by any suitable cement.

A separate nut may be applied to the tube 10 above the union and serve to compress the spring independently of the nut D', as will be understood.

Modifications may also be made in the forms and proportions of the several parts and in 15 the materials employed.

Although I have described the invention as applied to a basin in which the overflow-passage is formed in one therewith, it is adapted to serve with basins or similar receptacles 20 having independent overflow-passages.

I claim—

In a coupling of the character described, a metallic tube threaded at its lower end and

having tapered seat and annular flange at its upper end, said flange being corrugated upon 25 its under face, and the tube below the seat formed with openings, and grate below the openings, a nut secured to the threaded end of the tube, a union held by said nut, a soft washer beneath the corrugations of the flange, 30 a washer with a soft facing surrounding the tube below the openings, and a helical spring around the tube with one end bearing against the upper face of said nut and the other end against the under face of the soft-faced 35 washer to force the corrugations of the flange into the soft washer and the soft-faced washer against the under face of a basin, all substantially as and for the purpose specified.

In testimony that I claim the invention 40 above set forth I affix my signature in presence of two witnesses.

HENRY G. VOLKMAR.
